UNITED STATES PATENT OFFICE.

HARRY W. SMITH, OF WORCESTER, MASSACHUSETTS.

ELECTRIC-CIRCUIT CLOSER FOR LOOMS.

SPECIFICATION forming part of Letters Patent No. 691,979, dated January 28, 1902.

Application filed November 8, 1898. Serial No. 695,880. (No model.)

To all whom it may concern:

Be it known that I, HARRY W. SMITH, a citizen of the United States, residing at Worcester, in the county of Worcester and Commonwealth of Massachusetts, have invented a new and useful Improvement in Electric-Circuit Closers for Looms, of which the following is a specification, accompanied by drawings forming a part of the same, in which—

10 Figure 1 represents a portion of a loom-lathe, showing one of the shuttle-boxes in side elevation, with the binder and front of the shuttle-box removed in order to disclose the shuttle in the shuttle-box. Fig. 2 is a top view of the same. Fig. 3 is a central longitudinal sectional view of the bobbin removed from the shuttle. Fig. 4 is a transverse sectional view of the shuttle and bobbin on line 4 4, Fig. 2. Fig. 5 represents a vertical 15 longitudinal sectional view of a portion of a shuttle. Fig. 6 is a top view of a shuttle, showing a modified form of attaching the contact-strips thereto. Fig. 7 is a longitudinal sectional view of a portion of the shuttle 20 shown in Fig. 6, the section being taken on line 7 7, Fig. 6.

Similar reference-figures refer to similar parts in the different views.

My invention relates to looms provided with auxiliary mechanism for performing operations auxiliary to that of weaving—such, for example, as stopping the loom or supplying fresh filling thereto; and it has for its object to provide means for causing the action of such auxiliary mechanism at a predetermined period in the operation of the loom and prior to complete exhaustion of the filling.

Generally stated, the invention consists of a detecting means carried by the bobbin or weft-carrier, the weft or filling being laid upon the bobbin or carrier to one side of the detecting means in distinctive initial winds and thereafter wound to cover said detecting means and permit the weft or filling to be delivered from the end of the carrier or bobbin and to uncover the detecting means prior to complete exhaustion of the filling, and devices adapted to engage said detecting means and cause the operation of the auxiliary mechanism when said detecting means has become uncovered by the weft or filling.

The invention consists, further, of the con-

struction and combination of parts, that will be hereinafter more fully described, and definitely pointed out in the claims.

In the present embodiment of my invention I have shown the detecting means as a band on the bobbin or weft-carrier located at the base or head of the bobbin or carrier and the feeler devices as spring-fingers carried by the shuttle to engage the detecting means and complete an electric circuit; but it will be understood that these features of structure may be varied without departing from the spirit of my invention.

Referring to the accompanying drawings, which represent one embodiment of my invention, 1 denotes one end of the lathe of a loom, upon which is mounted a shuttle-box 2, containing a shuttle 3 in position at one end 70 of its movement through the fabric.

The shuttle-body 3 is provided with a weft-carrier, which in the present instance consists of a bobbin 5. (Shown on a larger scale in Fig. 3, where the broken lines 6 6 indicate the 75 outline of the weft when the bobbin is filled.) The weft-carrier is supported in any suitable manner in the bobbin-chamber 7^a of the shuttle.

The bobbin in the form represented in the drawings comprises a cylindrical body or section 7, a conical base 8, and a head 9, and the weft is wound thereon by beginning at the top of the conical section 8 or at its junction with the body-section 7 and traversing the weft-thread back and forth over the conical section 8 by the traversing mechanism of the winding or spinning machine, thereby forming a conical body of yarn next the head 9, as shown by the broken line 10, Fig. 3. The 90 traversing mechanism then builds upon the inclined surface of the yarn already wound, filling the bobbin toward its tip, as shown by the broken lines 6 6, Fig. 3. In the operation of weaving the weft is withdrawn from the end 95 of the bobbin and unwound in reverse order, that portion which is laid in conical form on the base 8 of the bobbin by what I term the "initial traversing movement" being last withdrawn.

Attention is directed to the method of winding bobbins of the class represented in the drawings, as the arrangement of my circuit-closing mechanism has reference to the order

of laying the weft upon the bobbin, as hereinafter described, although any other method of winding the bobbin which will leave a suitable amount of weft after the indication for the operation of the auxiliary mechanism will come within the scope of my invention.

- Preferably next to the head 9 and at the base of the conical section 8 of the bobbin I place a detecting means, preferably in the form of a metallic annular band 11, having its surface preferably raised above the adjacent surface of the bobbin, upon which yarn is wound, thereby forming a step 12, and contiguous to the step 12 I preferably form a groove or depression 13 in the surface of the bobbin, so that as the weft is laid upon the conical section 8 by the initial traversing movement extending from the apex of the conical section to the head 9 the winding will be limited by the step 12 until the conical body of the weft is brought flush, or nearly so, with the surface of the metallic band 11, forming a distinctive initial wind, as indicated by the broken lines 14 14, Fig. 3, when the winding is extended by the traversing movement over the band 11 to the head 9 forming the cone 10 10, which is built upon to form the body of yarn, as indicated by the broken lines 6 6, Fig. 3.
- Upon the top of the shuttle-body 3 are contact-strips 15 15, either flush or slightly raised in some portion above the surface of the shuttle-body, so they will be wiped by the warp-threads as the shuttle passes through the shed.
- As represented in the drawings, the contact-strips 15 are conveniently given a quarter-twist at 16 to bring their ends 18, which extend into the bobbin-chamber 7, into a vertical plane, so they will lie against the opposing side walls 17 17 of the bobbin-chamber. Yielding blades 19 19, electrically connected with the contact-strips 15, extend downwardly between the bobbin and the side walls 17 17 of the bobbin-chamber, preferably on opposite sides of the bobbin and in the plane of the band 11, which when brought into contact with the yielding blades 19 19, carried by the shuttle-body, acts to close the circuit. A bobbin filled with weft or filling, as above described, and provided with an electrical conducting-surface in one end is herein termed a "circuit-closer" bobbin. The blades 19 19, as shown, consist of elastic springs electrically connected at their upper ends to the ends 18 of the contact-strips 15 either by being directly attached to said strips, as shown in Figs. 4 and 5, or integrally therewith, as shown in Figs. 6 and 7, and having their lower ends housed by entering holes 20 20 in the body of the shuttle in order to prevent their entanglement with weft as it is withdrawn from the shuttle. The blades 19 19 at predetermined periods in the operation of the loom are made to form the terminals of an electric circuit, as hereinafter described, and they are made to project into the path of the bobbin as it is inserted in the bobbin-cham-

ber, so that the insertion of a bobbin will serve to crowd the yielding blades 19 19 out of its path and cause the blades to press against the weft on the bobbin in the plane of the annular band 11, so that as the weft is removed and the band 11 laid bare the yielding blades are brought into contact with the band, thereby electrically connecting the contacting strips 15 15. Insulated contact-brushes 21 21 are supported in a convenient position on the lathe and by means of the binding-screws 22 and the electric wires 23 and 24 are made a part of an electric circuit. The brushes 21 21 overhang the shuttle-box and extend into the paths of the contact-strips 15 15, so that as the shuttle enters the shuttle-box the contact-strips are brought into rubbing contact with the brushes 21 21. The brushes preferably consist of a pair of yielding metallic blades, which exert a downward pressure upon the shuttle as the contact-strips 15 15 come into contact with the brushes, thereby pressing the shuttle against the race-plate or top of the lathe. By employing an independent pair of brushes 21 21 instead of forming contact-surfaces on the shuttle-binder, as has heretofore been done, I am able to determine the point of contact during the flight of the shuttle across the lathe independently of the action of the shuttle-binder. As the pressure of the brushes against the shuttle is received by the race-plate or top of the lathe, the brushes may be located in any convenient position above the race-plate. So long as the yielding blades 19 19 are held out of contact with the band 11 by the weft the electric circuit remains open; but when the weft has been withdrawn sufficiently to expose the surface of the band the blades come into contact with the band and the electric circuit becomes closed and an electric current is established, which by energizing an electromagnet forming a part of the circuit is made to control any known auxiliary mechanism.

The closing of the electric circuit takes place as soon as the shuttle enters beneath the brushes 21 21 after the unwinding of the weft from the band 11 and while that portion of the weft denominated the "distinctive initial wind" remains which was wound upon the bobbin during the period while the initial traversing movement was limited by means of the step 12, including the accumulation of weft, in the groove or depression 13.

It will thus be seen that with the bobbin formed as above described and with the yielding blades 19 19 contacting with the weft only at the last portion of the weft to be removed from the bobbin there will be no friction upon the part of the weft which is being withdrawn from the bobbin during the process of weaving by its contact with the yielding blades until the weft is nearly all withdrawn. Consequently there is no such liability of breaking the weft as would be the case provided the yielding blades were so arranged

that the weft would be drawn from under and in contact with the blades at frequent intervals during the whole time of the withdrawal of the weft from the bobbin. By arranging 5 the yielding blades 19 19 to both contact on band 11 in the same plane I am enabled to detect the absence of the weft with great precision and also to use a narrow band for the conducting-surface, consisting of a ring surface, 10 rounding the bobbin, which will contact with both of the blades however the bobbin may be turned on its axis in placing it in the shuttle-body.

As above described, it will be seen that my circuit-closing device comprises not only a circuit-closer bobbin, but also what I term a "bobbin-adjusted blade"—that is, a yielding blade forming one of the terminals of the electric circuit which is carried by the shuttle-body and normally held in the path of the bobbin as the bobbin is inserted in the bobbin-chamber in the usual manner in the operation of weaving, so that the mere act of inserting a bobbin carrying the weft will move the yielding blade and cause it to press upon the weft in the plane of the contacting surface of the circuit-closer bobbin, thereby bringing the elements for completing the circuit which are carried by the shuttle into such operative relationship that the withdrawal of the weft from the band 11 will allow the pressure exerted by the yielding blade to bring it into contact with the band and electrically connect the contacting strips 15. In other words, the insertion of a full bobbin in the bobbin-chamber of the shuttle serves to set the yielding blade. In the circuit-closer bobbin represented in Fig. 3 I have raised the band 11 above the adjacent weft supporting the surface and formed a shoulder 12 next the band by placing a thin metallic band around the bobbin in the plane at right angles to its axis and upon a portion of the bobbin which is slightly raised, and I have increased the height of the step by forming a groove 13 next the band. I do not, however, confine myself to this specific form of construction, as the groove 13 may be omitted and the elevation of the band be accomplished by using a thicker band.

What I seek to accomplish is to so raise the contacting surface of a circumferential band during the initial traversing movement of the weft in winding the bobbin that the winding will stop short of the surface of the band until the desired quantity of weft has been wound on the bobbin, filling the space next the band, when the next traversing movement in winding the bobbin will cause the weft to be laid over the contacting surface of the band. By placing a contacting surface on the bobbin at the end of its weft or filling supporting surface opposite the delivery end of the bobbin and in the form of a narrow raised band lying in a plane at right angles to the axis of the bobbin, forming a shoulder which causes the weft to fall back during the

initial traversing movement in winding the bobbin, I am enabled to secure a reserve quantity of weft on the bobbin after the completion of the circuit and also to more sharply define the period of closing the circuit. To this end I also place the narrow metallic band near the end of the weft-supporting surface, with the opposite edges of the band lying in parallel planes and at right angles to the axis of the bobbin, so that the edges of the band will present the same angle to the line of movement of the weft as it is traversed in opposite directions over the weft-supporting surface of the bobbin and causing the weft to cross the band in both directions at a uniform angle thereto.

Instead of contact-strips 15 15 on the end of the shuttle-body long strips 25 can be employed, as shown in Fig. 6, thereby securing a longer rubbing contact with the brushes 21, which can be duplicated at the opposite end of the lathe. 85

I do not confine myself to the specific construction of my circuit-closing device as shown and described, as these may obviously be modified or changed without departing from the scope of my invention. 90

I do not herein separately claim the bobbin or filling-carrier having detecting means, as this forms the subject-matter of a divisional application filed by me, Serial No. 73,081, August 23, 1901. 95

What I claim as my invention, and desire to secure by Letters Patent, is—

1. The combination with a loom-shuttle body and a weft-bobbin carried therein, of a pair of yielding blades supported by the shuttle-body and arranged to bear against the bobbin on opposite sides thereof, whereby said blades are separated by the weft as the bobbin is inserted in the shuttle, said blades forming the terminals of an electric circuit, and a common contact-piece carried by the bobbin and arranged to be uncovered by the withdrawal of the weft from the bobbin, substantially as described.

2. The combination with a loom - shuttle body and a bobbin carried therein, of a pair 115 of yielding blades arranged to press against the bobbin on opposite sides thereof, whereby said blades are separated by the weft as the bobbin is inserted in the shuttle, said blades forming the terminals of an electric circuit, 120 and a metallic band extending circumferentially around said bobbin near one end of the surface covered by the weft and arranged to electrically connect said blades as the weft is withdrawn from said band, substantially as 125 described.

3. The combination with a loom shuttle-body and a bobbin carried therein, of a pair of yielding blades arranged to press against the bobbin and on opposite sides, whereby said blades are separated by the weft as the bobbin is inserted in the shuttle, contact-strips on said shuttle-body electrically connected with said blades, contact-brushes form- 130

ing the terminals of an electric circuit and overhanging into the path of said contact-strips as the shuttle moves into the shuttle-box, means for electrically connecting said blades as the weft is withdrawn from the bobbin, substantially as described.

4. In an electric-circuit closer for looms, the combination with a loom shuttle-body, of a pair of metallic contact-strips placed on the top side of the shuttle-body, and a pair of yielding blades, or metallic strips, forming contact-brushes supported by the lathe with their free ends overhanging the path of the shuttle and arranged to press against said contact-strips and exert a downward pressure on the shuttle against the race-plate, or top of the lathe, and means for connecting said contact-brushes with the poles of a battery, or other source of an electric current, whereby the contact-strips of the shuttle are electrically connected with said contact-brushes by the flight of the shuttle across the lathe, substantially as described.

5. The combination with a loom shuttle-body and a bobbin carried therein, of a pair of contact-strips arranged on the top of the shuttle-body and projecting above the surface of the shuttle-body to be rubbed by the warp in the operation of weaving, contact-brushes forming the terminals of an electric circuit and extending into the path of said contact-strips and means controlled by the weft on the bobbin for electrically connecting said strips, substantially as described.

35 6. In an electric-circuit closer for looms, the combination with a shuttle-body having a bobbin-chamber and a bobbin held therein, of a narrow metallic band surrounding the bobbin near the end of its weft-supporting surface and lying in a plane at right angles to the axis of the bobbin, said bobbin having a distinctive initial wind of weft or filling to one side of said metallic band and the weft or filling being thereafter wound upon the carrier to cover said band and to permit the weft or filling to be delivered from the end of the bobbin and to uncover the said band prior to complete exhaustion of the weft or filling, a yielding blade between the bobbin and the 50 vertical side wall of the bobbin-chamber and means for holding said blade normally in contact with the weft on said bobbin, substantially as described.

7. In an electric-circuit closer for looms, 55 the combination with a lathe, a shuttle-box, a shuttle-body, having a bobbin-chamber and a bobbin carried in said chamber, of contact-brushes carried by said lathe and overhanging said shuttle-box in the path of the shuttle, contact-strips attached to the top of the shuttle-body and arranged to be brought into contact with said contact-brushes as the shuttle moves into the shuttle-box, yielding blades electrically connected with said contact-strips and extending downward into said bobbin-chamber and on opposite sides of said bobbin and an electrical conducting-surface on said

bobbin in the plane of said yielding blades, substantially as described.

8. In an electric-circuit closer for looms, 70 the combination with a lathe, a shuttle-box, a shuttle-body having a bobbin-chamber and a bobbin contained therein, of electrical contact-strips carried by the shuttle-body, contact-brushes carried by the lathe and extending into the path of said shuttle-strips, curved yielding blades attached at one end to said shuttle-strips and extending into the bobbin-chamber with their free ends entering holes in the body of the shuttle, and an electrical 80 conducting-surface on said bobbin in the plane of said yielding blades, substantially as described.

9. In an electric-circuit closer for looms, a shuttle-body having two contact-plates arranged to be brought into contact with the warp as the shuttle passes through the shed, means for bringing said plates into an electric circuit as the shuttle enters the shuttle-box, movable members electrically connected 90 with said contact-plates and arranged to press against the weft, and means for electrically connecting said movable members as the weft is removed, substantially as described.

10. The combination with a loom shuttle-body and a bobbin carried therein, of a pair of contact-strips on the outer surface of the shuttle-body, a pair of contact-brushes forming the terminals of an electric circuit, yielding blades electrically connected with said contact-strips and arranged to press against the weft on opposite sides of the bobbin, whereby said blades are separated by the weft as the bobbin is inserted, and a metallic band on said bobbin in the plane of the contact of said blades and arranged to be covered by the weft and uncovered as the weft is withdrawn in the operation of weaving; substantially as described.

11. The combination with a loom shuttle-body and a bobbin carried therein, of a pair of contact-strips carried by the shuttle-body, a yielding contact-blade electrically connected with one of said contact-strips and normally held in the path of the bobbin, and adapted to be crowded to one side by the bobbin as it is inserted in the shuttle-body, and a circumferential band near one end of the weft-supporting surface of the bobbin, said bobbin having a distinctive initial wind of weft or filling to one side of said band, the weft or filling being thereafter wound upon the bobbin to cover said band and permit the weft or filling to be delivered from the end of the bobbin and to uncover the band prior to complete exhaustion and means for electrically connecting said band with the other of said contact-strips, substantially as described.

12. In an electric-circuit closer for looms, the combination of a shuttle-body having a 130 bobbin-chamber, a pair of fixed brushes forming the terminals of an electric circuit, a pair of contacting strips carried by the shuttle and arranged to be periodically brought into con-

tact with said brushes, yielding blades electrically connected to said strips and normally held in the path of the bobbin as it is inserted in said bobbin-chamber, and a circuit-closer carried near the end of the weft-supporting surface and opposite the delivery end of the bobbin and in the plane of said yielding blades, whereby it is brought into contact with said blades as the weft is removed, substantially as described.

13. In an electric-circuit closer for looms, the combination of a shuttle-body, a weft-carrier or bobbin provided with detecting means and having a distinctive initial wind of filling thereon to one side of the detecting means, the filling being thereafter wound upon the carrier or bobbin to cover said detecting means and permit the filling to be delivered from the end of the carrier or bobbin and uncover the detecting means prior to complete exhaustion of the filling, and a feeler arranged to engage the detecting means when the weft has been removed to uncover the same.

14. In a circuit-closer for looms for controlling the operation of auxiliary mechanism, a shuttle-body, a weft or filling carrier adapted to be supported therein and provided with detecting means, said weft or filling carrier having a distinctive initial wind of weft or filling thereon to one side of the detecting means, the weft or filling being thereafter wound upon the carrier to cover said detecting means and permit the weft or filling to be delivered from the end of the carrier and uncover the detecting means prior to complete exhaustion of the weft or filling and a feeler device carried by the shuttle and adapted to engage the detecting means when the weft or filling has been unwound to uncover the detecting means.

15. In a circuit-closer for looms for controlling auxiliary mechanism, a shuttle-body, a filling-carrier or bobbin adapted to be supported therein, and provided with a contact or detecting member constituting a circuit-closing device normally covered by the filling during the weaving operation, feeler devices in electric circuit adapted to contact with the detecting member and close the circuit upon exhaustion of the filling to a predetermined amount.

16. In an electric-circuit closer for looms, the combination of a shuttle-body provided with a weft-carrier or bobbin supporting means and contact-strips, a weft-carrier or bobbin having a metallic contact part, and yielding fingers arranged one on each side of the shuttle-body with the weft-carrier or bobbin between them.

17. In an electric-circuit closer for looms, the combination of a shuttle-body provided with contact-strips and weft-carrier or bobbin supporting means, a weft-carrier or bobbin having a metallic contact part on a portion only of its weft-supporting surface, and yielding feelers arranged in the shuttle-body and maintained in separated relation by the weft and adapted to move toward each other as the weft approaches exhaustion to thereby contact with the metallic contact part on the weft-carrier or bobbin.

18. In an electric-circuit closer for looms, the combination of a shuttle-body provided with a weft-carrier or bobbin supporting means, a weft-carrier or bobbin provided with detecting means and having a distinctive initial wind of weft or filling thereon to one side of the said detecting means, the weft or filling being thereafter wound upon the carrier or bobbin to cover said detecting means and permit the weft or filling to be delivered from the end of the carrier or bobbin and to uncover the detecting means prior to complete exhaustion of the filling, and yielding fingers arranged at each side of the carrier or bobbin to engage the detecting means when it has become uncovered by the withdrawal of weft or filling.

19. In an electric-circuit closer for looms, the combination of a shuttle-body with means for supporting a weft-carrier or bobbin therein, a weft-carrier or bobbin provided with a metallic band and having a distinctive initial wind of weft or filling to one side of said band, the weft or filling being thereafter wound upon the carrier to cover said metallic band and permit the weft or filling to be delivered from the end of the carrier or bobbin and uncover the metallic band prior to complete exhaustion of the weft or filling, and yielding feelers carried by the shuttle to contact with said metallic band when the same has become uncovered.

20. In an electric-circuit closer for looms for controlling the operation of auxiliary mechanism, the combination of a shuttle-body, a weft or filling carrier adapted to be supported thereby and provided with a detecting means, said weft-carrier or bobbin having a distinctive initial wind of weft or filling to one side of said detecting means, the weft or filling being thereafter wound upon the weft-carrier or bobbin to cover said detecting means and permit the weft or filling to be delivered from the end of the carrier or bobbin and uncover the detecting means prior to complete exhaustion of the filling, and devices co-operating with said detecting means when the same has become uncovered by the withdrawal of the weft or filling, to cause the operation of the auxiliary mechanism.

HARRY W. SMITH.
